UNITED STATES PATENT OFFICE.

FELIX HUNTAR, OF NEW YORK, N. Y., ASSIGNOR TO AMERICAN CAN COMPANY, OF NEW YORK, N. Y., A CORPORATION OF NEW JERSEY.

PROCESS AND APPARATUS FOR CLOSING FILLED CANS.

Application filed April 10, 1920. Serial No. 372,965.

To all whom it may concern:

Be it known that I, FELIX HUNTAR, a citizen of the United States, residing in New York, in the county of New York and State 5 of New York, have invented a new and useful Improvement in Processes and Apparatus for Closing Filled Cans, of which the following is a specification.

This invention relates in general to the 10 applying of can ends to filled can bodies and while the invention has more particular reference to cans containing solid materials, as sardines, it will be manifest that it has broader application.

15 The principal object of the invention is the provision of an apparatus which will permit the can end to be placed on the can body and pressed down tightly thereagainst so that the contents may be compressed or 20 brought to a sufficiently low level to permit accurate seating of the end or cover on the body and which will permit also the cans to be removed from the end feeding station and held in this pressed relation until other 25 and further operation, as for example processing and the like, is accomplished.

In the feeding of a sardine can considerable difficulty and annoyance has resulted 30 from the tendency of the end to be displaced by upward pressure of the contents or through imperfect seating of the end in its initial application, and effort has been made to overcome this by applying the end in interlocked relation with the body either 35 by conjointly bending the same or providing the end with bent flanges into which flanges of the can body are inserted or threaded.

40 My invention contemplates a much simpler, more effective and positive apparatus and process wherein the end is pressed down directly upon the can body and there maintained by being held in pressed relation obviating any necessity of threading one 45 flange of one part into flanges of another or performing any mechanical operation calculated to provide an interlocking relation between the parts.

Another object of my invention is the 50 provision of an apparatus having this and other advantages which will insure against the release or delivery of any can end when there is no can body there to receive it.

Another object of the invention is the 55 provision of simply and easily manufac-

tured apparatus for the purpose mentioned, the parts of which will be so constructed and arranged as to minimize occasion for repair and replacement and which will reduce the necessity for adjustment of the 60 parts of the apparatus. In connection with the last named object it is pointed out that apparatus of this character is usually used by packers and canners, many of whom are without expert machinists and mechanics 65 and without a machine shop equipment, and since the product canned must be handled with extreme expedition after it is received any loss of time required through the incapacitation of the apparatus for any cause 70 is extremely costly.

Numerous other objects and advantages of the invention will be apparent as it is better understood from the following description when considered in connection 75 with the accompanying drawing illustrating a preferred embodiment thereof.

Referring to the drawings:

Figure 1 is a side elevation of so much of a can control apparatus as is believed necessary to an understanding of the present invention;

Figure 2 is a top plan view thereof;

Figure 3 is a section taken substantially on the line 3—3 of Figure 1;

Figure 4 is a section taken substantially on the line 4—4 of Figure 2;

Figure 5 is a section taken substantially on the line 5—5 of Figure 3;

Figure 6 is a section taken substantially on the line 6—6 of Figure 2;

Figure 7 is a section taken substantially on the line 7—7 of Figure 2;

Figure 8 is a partial section taken substantially on the line 8—8 of Figure 6 on an enlarged scale;

Figure 9 is a partial section on an enlarged scale taken on the line 9—9 of Figure 3;

Figure 10 is a section similar to Figure 8 with the parts arranged in different positions;

Figure 11 is a section similar to Figure 9 with the parts arranged in different positions;

Figure 12 is a partial detailed view, as 105 will be later explained.

For the purpose of illustrating this invention, there is shown on the drawings, an intermittent conveyer comprising two chains 10 having upstanding flange body advanc-

ing lugs or means 16 and movable in slots 17 in a suitable table or can support 18.

This conveyer moves past a can end feeding station at which, in the present instance, 5 is located a stack holder comprising rods 19 extending up from a can end feeding head 21. This head comprises a base 22 mounted in relation to the table in any suitable fashion and preferably so that the table extends out 10 at each side and the conveyer moves past the feeding station, the intermittent action being such that each can is brought to rest at this station as will be readily understood. Mounted above the conveyer travel and sup- 15 ported from the base plate 22 is a head plate 23 in which the rods 19 are positioned, this plate having legs 24 resting on the bed plate and held in place by bolts 25 (Fig. 3). The stack holder is adapted to contain a stack of 20 ends or covers, in registration with and extending down into an opening 26 through the head plate and directly above the position assumed by the cans as they are brought to rest at this can end receiving station. The 25 stack of ends normally rest upon a pair of retractable stack supports 27 mounted in ways 28 in opposite sides of the head plate. Just above each said stack support 27 is provided a separator 29 adapted to be projected 30 into the opening 26 and above its companion support 27 to separate the bottommost end from the stack and to support the stack while the support 27 is withdrawn to permit the can end to move down upon the can body. Each support 27 and its companion separator 29 are caused to alternately reciprocate into and out of operative position when and only when a can body has been positioned beneath the stack to receive an end. 35 The mechanism shown on the drawing for feeding the end in this manner will now be described.

Referring to Figures 1, 2, 3 and 4 it will be noted that an eccentric 31 is mounted upon 40 a shaft 32 which may be taken to be a power shaft of the machine and which for the purposes of the invention may be considered a source of power. The eccentric 31 is adapted to actuate an eccentric rod 33 to which 45 is pivoted at 34 an arm 35 fixed upon a shaft 36 having bearings in bearing brackets 37 which extend down from beneath the base plate 18. The bearing 34 is a block bearing and is held against a stop 38 on the rod 33 50 by a spring 39. The shaft 36 is thus given an oscillating movement by the rod 33 and eccentric 31. This shaft extends clear across the apparatus (Fig. 3) and is provided with an arm 41 having a laterally extending lug 55 42 to which is pivoted a link 43 in turn connected with an arm 44 pivoted upon a shaft 45 having bearings in legs 24. The arm 44 carries a latch plate 46 adapted for engagement with a shoulder 47, on a latch arm 48 60 pivoted at 49 upon a double lever or yoke 65

lever 51 also pivoted upon the shaft 45. The construction of this yoke lever is best shown in Figure 4 from which it will be noted that two arms 52 have bearing on the shaft 45 and that these arms are connected by a cross member 53 preferably integral with the arms. At each side a link 54 (Fig. 2) is pivoted at 55 in an upstanding lug 56 on the yoke and connected with an arm 57 fixed on the upper end of a shaft 58 extending down through a bearing lug 59 in the head plate (Fig. 6) and having a plate or lever 61 fixed on its lower end. Two pins 62 and 63, Figures 9 and 10, extend down and have pivot bearing respectively in the tails 64 and 65 80 of the can end supports 27 and the separators 29. The tail of the separator is cut away, as indicated at 66, and the opening 28 is so arranged (Figs. 8 and 10) that these can supports and separators may have a slightly 85 arcuate movement in their reciprocation. The plate or lever 61 may cause opposite reciprocation of its companion support and separator upon movement from the position shown in Figures 8 and 9 to that shown in Figures 9 and 10 and of course a return corresponding movement. The latch arm is normally held disengaged from the latch plate by a lever 71 (Figs. 5 and 7) pivoted at 72 on a post provided for the purpose. This lever is pulled by a spring 73 to extend into the path of travel of the can body in approaching the end receiving station. When thus arranged the tail of the lever holds the latch arm out of position 90 for engagement by the latch plate. A can approaching the station pushes the lever against the force of the spring permitting the latch to drop into can end delivering position by gravity and the feeding of the 100 can end results.

I provide means at each side of the cans for pressing the covers or ends down tightly thereupon to compress the contents and accurately seat the same upon the body. This 110 means comprises wings 74 (Figs. 4 and 7) extending out from a sleeve 75 pivoted on shaft 45 at one side, a similar arrangement being provided upon a shaft 76 at the other (Figs. 7 and 12). Actuating means are provided for swinging these wings downwardly and onto the top of the can body in the manner to be observed upon comparing Figures 7 and 12. At each side of the apparatus arms 77 (Fig. 1) extend out from the shaft 36 and these arms are connected by links 78 with lugs 79 extending out from the sleeves 75. This action is so timed that it occurs after the end is positioned and just before the can body starts to move from the can end receiving station. I also provide means for holding the can ends thus 120 pressed down upon the body after the can body passes from the influence of the wings 74 and during its subsequent transfer by 130

the conveyer, which for the purpose of this invention may be considered to convey it during subsequent operations. This means consists in the present instance of guides 81 (Figs. 3 and 6) having curved or bevel ends 81' and arranged to extend down from beneath the top plate 23 at the discharge side. These guides may be connected by plate 82 with similar guides 83 extending along 10 above the travel of the conveyer and the dimensions of the parts being such that the can end is held substantially in contact with the top of the body as the can is moved ahead.

15 The can end is thus pressed down upon the top of the body by pressure exerted upon the upper face of the end and the under face of the body and this pressure is maintained in like manner so long as may be desirable. 20 In other words the can thus held may be passed through an oven or other processing apparatus, or if desired merely through means to secure the end in place.

It is thought that the invention and many 25 of its attendant advantages will be understood from the foregoing description, and it will be apparent that various changes may be made in the form, construction and arrangement of the parts without departing 30 from the spirit and scope of the invention or sacrificing its material advantages, the form hereinbefore described being merely a preferred embodiment thereof.

I claim:

35 1. In an apparatus for feeding can ends to filled can bodies, the combination of devices for advancing can bodies to the can end receiving station, devices for placing a can end on the can body at said station and 40 subsequently acting means at said station for pressing said end down upon said body while the latter is in its can end receiving position.

2. In an apparatus for feeding can ends to 45 filled can bodies, the combination of a conveyer movable to bring said bodies to a can end receiving station, devices at said receiving station for positioning a can end on a can body, means at said station coaxial with 50 said positioning devices for pressing said end down upon said body and means for retaining said end in said pressed relation after the can is removed from said station.

3. In an apparatus for feeding can ends 55 to filled can bodies, the combination of a conveyer movable past the can end feeding station, devices at said station for positioning the can end upon a can body, and coaxial therewith a downwardly acting can end 60 compressing means, and means associated with said conveyer on the discharge side of said station for holding said end firmly down against the body and contents therein contained.

65 4. In an apparatus for feeding can ends to

filled can bodies, the combination of a conveyer movable past the can end feeding station, devices for feeding a can end to said can body at said can station means at the sides of the cans and movable over and down 70 upon the can ends for pressing the same down to compress the contents within the can, and overhead guides for maintaining said end in pressure relation with said body and said contents as the can is advanced by 75 the conveyer beyond said station.

5. In an apparatus for feeding can ends to filled can bodies, the combination of means for positioning a can at a feeding station, means for placing an end on the body, pressure means comprising movable wings 74 arranged near the sides of the cans for engaging the upper face of the can end after it is positioned on the body for pressing said end down upon said body to compress the contents within the can.

6. In an apparatus for feeding can ends to filled can bodies, the combination of means for positioning a can at a feeding station, means for placing an end on the body, pivoted pressure means arranged near the side of the cans and swingable over the path of the cans for engaging the upper face of the can end after it is positioned on the body for pressing said end down upon said body to compress the contents within the can.

7. In an apparatus for feeding can ends to filled can bodies, the combination of means for positioning a can at a feeding station, means for placing an end on the body, pivoted pressure means engaging the upper face of the can end after it is positioned on the body for pressing said end down upon said body to compress the contents within the can, means for advancing the can body and downwardly pressed can end from said station, and guides extended beyond said station and bearing upon the top of said ends for holding them in pressed relation on said can bodies, whereby the can bodies, can ends and contents so held may be conducted to a processing station and the like.

8. In an apparatus for feeding can ends to filled can bodies, the combination of an endless chain conveyer for moving the cans to a can end feeding station, a stack holder for can ends at said station, means for singly separating can ends from the stack, means for pressing the can ends down upon the filled can bodies after they have been fed to the same and before said body moves from said station, and guides arranged above said conveyer for holding the can ends compressed on the can bodies after they leave said can end feeding station and until the filled cans are operated on at another succeeding station.

9. A process for supplying ends to cans having a solid content, which consists in filling the cans to a height above the point

80

130

which the bottoms of the can ends will occupy when tightly pressed down on the cans, and then placing said ends on the cans and pressing down the contents by pressure exerted upon the ends and maintaining said pressure on the can ends during subsequent operation.

10. A process which consists in filling the can body to a height above the point which

the bottoms of the can end will occupy when tightly pressed down on the can body, and then pressing the end upon the can body, squeezing the can body and end between members applied at the under surface of the can body and the surface of the can end to press the content in the can and transporting the can so held for subsequent operation.

FELIX HUNTAR.
